UNITED STATES PATENT OFFICE

108,782

DESIGN FOR A LAMP OR SIMILAR ARTICLE

Carl J. Forslund, Brooklyn, N. Y.

Application January 13, 1938, Serial No. 74,267

Term of patent 7 years

To all whom it may concern:

Be it known that I, Carl J. Forslund, a citizen of the United States, residing at Brooklyn, in the city, county, and State of New York, have invented a new, original, and ornamental Design for a Lamp or Similar Article, of which the following is a specification, reference being had to the accompanying drawing, forming part thereof.

or similar article showing my new design; and Fig. 2 is a side elevational view thereof.

The dominant features of my design reside in the parts shown in solid lines.

I claim:

The ornamental design for a lamp or similar article as shown and described.

CARL J. FORSLUND.
